UNITED STATES PATENT OFFICE

166,356

TRAY

Joseph A. Potchen, Grand Rapids, Mich.

Application May 8, 1950, Serial No. 9,772

Term of patent 14 years

(Cl. D44—10)

To all whom it may concern:

Be it known that I, Joseph A. Potchen, a citizen of the United States, residing in Grand Rapids, county of Kent, State of Michigan, have invented a new, original, and ornamental Design for a Tray, of which the following is a specification, reference being had to the accompanying drawing, forming a part thereof.

I claim:

The ornamental design for a tray, substantially as shown.

JOSEPH A. POTCHEN.
